James Cooper of Brown County Ohio
Letters Patent

This Schedule refers to in the following Patent and making part of the same, containing a description in the said James Cooper himself of his improvement in the machine for thrashing clover and other small seed.

Be it known that I James Cooper of Brown County, State of Ohio have made a new and useful improvement in the machine for thrashing out clover and other small seeds, which is described as follows, reference being had to the annexed drawing of the sum making part of this Specification. This machine consists of the following principal parts. 1. The frame. 2. The concave or bed. 3. The thrashing or rubbing cylinder. 4. The hopper. 5. The grain. 1. The frame of marked A in the drawing is made similar to the frame of a common thrashing machine, of sufficient size and strength to contain and support the machinery hereinafter described. 2. The concave or bed B is made in the following manner. Make a box C as wide as the cylinder is long with a few bottom D, fill this box with straw E placed concave; then fix a moveable board F, or pieces of timber in one end of the box against the straw and force it forward by means G, a wedge or compass, the straw next to the cylinder are then to be cut off in such a manner as to form a concave, corresponding to the cylinder and extending half round it, or the contrary. This box and concave are then placed under the cylinder in the frame.

The concave may also be formed by placing the cylinder in the box and then inserting the straw through the bottom of the box with the ends thereof resting against the circumference of the cylinder which will form the concave without the necessity of cutting it out. The moveable board is to be driven against the straw by means of the wedge or wedge, as before described and directed, after which the lower end of the straw are to be cut off and a slide or board placed against the straw and

and turned on grooves, or by screws, to keep the stone firmly in its place. Instead of straw for the bed the material may be broken wood cut in fine shavings, bristles, & shavings of grass, whale bone split or any similar material, compressed in the manner before described.

3. The thrashing or rubbing cylinder No. 1 is made by sawing basal fir groves, lengthwise the cylinder around its whole circumference, into which are inserted plates of metal and in front of each plate the wood of the cylinder is cut away in order to form a notched plate or groove, and when the edges of the plates are worn down close with the wood, the notches or grooves, may be removed by again trimming away the wood in front of the plates. 4. The hopper L. is made in the usual manner. 5. The gearing consists of a pulley No. 1 on the end of the shaft of the thrashing cylinder, ... around which passes a band leading to the pulley of the driving power.

Operation. The machine being put in motion by manual, horse or other power, the seed to be rubbed out is put into the hopper when it is struck or caught by the notches, flutes, or bars of the cylinder and forced over the end of the stone of the bed which separates the seed from the hulls. What I claim as my invention and which I desire to secure by letters Patent consists in the before described mode of making the concave or bed, of straw, broken bristles, split whale bone, or of other similar material. Also the mode of using the cylinder.
